UNITED STATES PATENT OFFICE.

WHELOCK HUBBELL AND ASA J. ANNIS, OF SILOAM SPRINGS, ARKANSAS.

RAILROAD-TIE.

No. 904,331.

Specification of Letters Patent.

Patented Nov. 17, 1908.

Application filed May 21, 1908; Serial No. 434,024.

To all whom it may concern:

Be it known that we, WHELOCK HUBBELL and ASA J. ANNIS, citizens of the United States, and residents of Siloam Springs, in the county of Benton and State of Arkansas, have invented a new and Improved Railroad-Tie, of which the following is a full, clear, and exact description.

The object of our invention is to provide a railroad tie, which may be constructed of metal or concrete and to which may be bolted a rail chair, lugs with sleeves being provided, the sleeves being adapted to fit the rail chair, and the lugs being adapted to engage the base of the rail to hold it in place, there being disposed between the rail and the rail chair, wedge-shaped blocks of wood or other similar material which not only serve as cushions for the rail, but which also may be used to force the rail into alinement, the lugs being adjustable by means of their sleeves to hold the rails securely in their new position.

In this specification we will describe the preferred form of our invention, but it will be understood that we do not limit ourselves thereto, as we consider ourselves entitled to all forms and embodiments of the invention which may be held to fall within the scope of the appended claims.

In the drawings similar reference characters refer to similar parts in all the figures, in which

Figure 1 is a transverse section of a rail showing it adjusted to one of our rail chairs and to the transverse channel member, the channel member and portions of the rail chair being shown in section; Fig. 2 is a plan view of the same, a portion being shown in section on line 2—2 of Fig. 1; Fig. 3 is a side sectional elevation of the same on the line 3—3 of Fig. 1; and Fig. 4 is a perspective view showing our invention with a rail adjusted and secured in position for service.

By referring to the drawings it will be seen that our invention is used with the ordinary type of rail 1, and that we provide a transverse channel member 2, which is adapted to extend across the road bed from rail to rail, there being disposed in this transverse channel member 2 a rail chair 3, which is adapted to fit securely the transverse channel member 2. This rail chair 3 has a horizontal portion 4 and side vertical portions 5, the said vertical portions 5 being spaced apart to permit of the base of the rail 1 be-

ing adjusted therebetween. Each of the side vertical portions 5 has a vertical orifice 6 extending therethrough, this orifice being kept close to the intersection of the horizontal portions 4 and the vertical portions 5 of the chair 3, so that the orifices 6 will be open to the inner faces of the vertical side portions 5.

We provide sleeves 8 with lugs 7 integral therewith, the sleeves 8 being adapted to fit the vertical orifices in the side portions 5 of the rail chair, and the lugs 7 being adapted to extend through the openings in the inner faces of the vertical side portions 5 of the rail chair 3, so that the lugs will be so disposed as to engage the base of the rail 1.

The transverse channel member 2 has openings 9 in its bottom, the centers of which are in alinement with the centers of the vertical orifices 6, so that a bolt 10 may be disposed through the bottom of the transverse channel member 2 into the orifice 6 through the sleeve 8 to the top of the side portions 5, so that a nut 11 with a washer 12 may be adjusted to the top to hold the rail chair 3 and the sleeve 8 with its lug 7 firmly in the transverse channel member 2.

The bolt 10 may have its portion extending through the transverse channel member 2 angular in form, so that it may fit the surfaces of the orifice 9 in the transverse channel member 2, to prevent its rotation when the nut 11 is screwed home.

Between the horizontal portions 4 of the rail chair 3 and the face of the rail 1 we dispose wedge-shaped members 13, which have their bases disposed at opposite ends of the rail chair 3 so that, when adjusted together, the angles being equal, the surface in contact with the base of the rail 1 and the surface in contact with the horizontal portion 4 of the rail chair 3, are parallel. These wedge-shaped members may be of wood or other similar material, so that they will serve as a cushion for the rail, and they also serve to hold the rail 1 in alinement by driving their bases toward or away from the rail chair 3, which will cause their surfaces against the base of the rail 1 and the horizontal portion 4 of the rail chair 3 to be disposed at a greater or less distance from each other.

In using our invention, the transverse channel member 2 is disposed in place on the road bed with the bolts extending therethrough, and the rail chairs 3 are placed in

position with the sleeves 8 with the integral lugs 7, disposed in the orifices 6 of the side portions 5 of the rail chair 3.

The wedge-shaped members 13 are then placed in position with their bases at opposite sides when the rail 1 is disposed thereon, the lugs 7 being disposed on the upper surface of the base of the rail. A washer is then disposed on the bolt 10 and the nut 11 is secured to the bolt. Should it be found that the rail must be raised or lowered, the nut 11 is unscrewed and the bases of the wedge-shaped members 13 are forced together or apart, as may be necessary, until the proper adjustment has been obtained, and the nuts 11 are screwed home, and the invention is ready for service.

Having thus described our invention, we claim as new and desire to secure by Letters Patent:

1. In a railroad tie, a transverse channel member a rail chair secured thereto, there being a recess in the rail chair, and a wedge cushion which is disposed in said space.

2. In a railroad tie, a rail chair, there being a vertical opening in the rail chair which extends laterally through its inner face for a portion of its height, a lug secured to a stem, the stem being disposed in the vertical opening in the rail chair, means to secure the lug to the rail and the rail chair to the tie.

3. In a railroad tie, a rail chair, there being a vertical opening therein which extends laterally through its inner face for a portion of its height, a lug secured to a stem, the stem being adapted to fit the vertical opening in the rail chair, and means to secure the lug to the rail chair and to a rail.

4. In a railroad tie, a rail chair, which is substantially right-angular in form, the horizontal portion being adapted to act as a foundation for the rail, the vertical portion having an orifice therein, a lug on a stem, the stem being adapted to fit the said orifice, and means to secure the stem to the rail chair and the lug to the rail.

5. In a railroad tie, a rail chair, which is substantially right angular in form, the horizontal portion being adapted to act as a foundation for the rail, the vertical portion having an orifice therein which extends laterally through its inner face for a portion of its height, a lug on a stem, the stem being disposed in the said orifice, and means to secure the said stem to the rail chair and the lug to the rail.

6. In a railroad tie, a rail chair which is substantially right angular in form, the horizontal portion being adapted to act as a foundation for a rail, the vertical portion having an orifice therein, a lug on a stem, the stem being adapted to fit the said orifice, means to secure the stem to the rail chair and the lug to a rail, and a wedge-shaped member which is adapted to be disposed between the

rail and the horizontal portion of the rail chair.

7. In a railroad tie, a rail chair, which is substantially right angular in form, the horizontal portion of which is adapted to act as a foundation for a rail, the vertical portion having an orifice therein, the said orifice extending laterally through its inner face for a portion of its height, a lug on a stem, the stem being disposed in said orifice, means to secure the stem to the rail chair and the lug to a rail, and a wedge-shaped member which is adapted to be disposed between the rail and the horizontal portion of the rail chair.

8. In a railroad tie, a rail chair which is substantially right angular in form, the horizontal portion being adapted to act as a foundation for a rail, the vertical portion having a vertical orifice therein, a lug on a sleeve, the sleeve being disposed in the orifice in the rail chair, and a bolt which is disposed through the sleeve and is adapted to secure the sleeve to the rail chair and the lug to a rail.

9. In a railroad tie, a rail chair, which is substantially right angular in form, the horizontal portion being adapted to act as a foundation for a rail, the vertical portion having a vertical orifice therethrough, a lug on a sleeve, the sleeve being disposed in the orifice in the rail chair, a bolt which is adapted to pass through the sleeve to secure the lug to the rail chair and to a rail, and a wedge-shaped member which is adapted to be disposed between the rail and the horizontal portion of the rail chair.

10. In a railroad tie, a rail chair, which is substantially right angular in form, the horizontal portion being adapted to act as a foundation for the rail, the vertical portion having a vertical orifice therethrough which extends laterally through its inner face for a portion of its height, a lug on a sleeve, the sleeve being disposed in said orifice of the rail chair, and a bolt which is adapted to pass through the sleeve to secure the sleeve to the rail chair and the lug to a rail.

11. In a railroad tie, a rail chair which is substantially right angular in form, the horizontal portion being adapted to act as a foundation for a rail, a vertical portion having a vertical orifice therethrough which extends laterally through its inner face for a portion of its height, a lug on a sleeve, the sleeve being disposed in the said orifice in the rail chair, a bolt which is adapted to pass through the sleeve and to secure the lug to the rail chair and to a rail, and a wedge-shaped member which is adapted to be disposed between the rail and the horizontal portion of the rail chair.

12. In a railroad tie, a transverse member, a rail chair which is substantially right angular in form, the horizontal portion being adapted to act as the foundation for the

5 rail, the vertical portion having a vertical orifice therethrough, the rail chair being disposed on the transverse member with the center of the said orifice in alinement with the center of an orifice in the said transverse member, a lug on a sleeve, the sleeve being disposed in the orifice in the rail chair, and a bolt which is adapted to pass through the sleeve and to secure the lug to a rail, the 10 sleeve to the rail chair and the rail chair to the transverse member.

13. In a railroad tie, a transverse member, a rail chair, which is substantially right angular in form, the horizontal portion being adapted to act as a foundation for a rail, the vertical portion having a vertical orifice therethrough which extends laterally through its inner face, the rail chair being adapted to be disposed on the transverse member with the center of the said orifice substantially in alinement with the center of an orifice in the center of the said transverse member, a lug on the sleeve, the sleeve being disposed in the orifice in the rail chair, and a bolt which is adapted to pass through the sleeve and to secure the lug to a rail, the sleeve to the rail chair and the rail chair to the transverse member.

14. In a railroad tie a transverse member, a rail chair which is substantially right angular in form, the horizontal portion being adapted to act as a foundation for a rail, the vertical portion having a vertical orifice therethrough, the rail chair being disposed on the transverse member with the center of the said orifice substantially in alinement with the center of an orifice in the said transverse member, a lug on a sleeve, the sleeve being disposed in the orifice in the rail chair, a bolt which is adapted to pass through the sleeve to secure the lug to a rail, the sleeve to the rail chair and the rail chair to the transverse member, and a wedge-shaped member which is adapted to be disposed between the rail and the horizontal portion of the rail chair.

15. In a railroad tie, a transverse member, a rail chair which is substantially right angular in form, the horizontal portion being adapted to act as a foundation for a rail, the vertical portion having a vertical orifice therethrough which extends laterally through its inner face, the rail chair being adapted to be disposed on the transverse member with the center of the said orifice substantially in alinement with the center of an orifice in the said transverse member, a lug on a sleeve, the sleeve being disposed in the orifice of the rail chair, a bolt which is adapted to pass through the sleeve and secure the lug to the rail, the sleeve to the rail chair, and the rail chair to the transverse member, and a wedge-shaped member which is adapted to be disposed between the rail and the horizontal portion of the rail chair.

16. In a railroad tie, a transverse member, a rail chair which is substantially right angular in form, and which fits the said transverse member, the horizontal portion being adapted to act as a foundation for a rail, the vertical portion having a vertical orifice therethrough which extends to its inner face for a portion of its height, the center of the said orifice being substantially in alinement with the center of an orifice in the center of the said transverse member, a lug on the sleeve, the sleeve being disposed in the orifice in the rail chair, a bolt which is adapted to pass through the sleeve and to secure the lug to the rail, the sleeve to the rail chair and the rail chair to the transverse member, and a wedge-shaped member which is adapted to be disposed between the rail and the horizontal portion of the rail chair.

17. In a railroad tie, a transverse channel member, a rail chair, which has a horizontal portion and two side vertical portions, the vertical portions having orifices therethrough, the rail chair being disposed on the transverse channel member with the centers of its orifices substantially in alinement with the centers of orifices in the said transverse channel member, lugs on sleeves, the sleeves being disposed in the orifices in the rail chair, and bolts which are adapted to pass through the sleeves to secure the lugs to opposite sides of a rail, the sleeves to the rail chair and the rail chair to the transverse channel member.

18. In a railroad tie, a transverse channel member, a rail chair which has a horizontal and two vertical portions, the vertical portions having vertical orifices therethrough which extend laterally through their inner faces for a portion of their height, the rail chair being disposed on the transverse channel member with the centers of its orifices substantially in alinement with centers of orifices in the side transverse channel member, lugs on sleeves, the sleeves being disposed in the orifices in the rail chair, and bolts which pass through the said sleeves and which are adapted to secure the lugs to opposite sides of a rail, the sleeves to the rail chair, and the rail chair to the transverse channel member.

19. In a railroad tie, a transverse channel member, a rail chair which has a horizontal and two side vertical portions, the vertical portions having vertical orifices therethrough which extend laterally through their inner faces for a portion of their height, the rail chair being disposed on the transverse channel member with the centers of its orifices substantially in alinement with centers of orifices in the said transverse channel members, lugs on sleeves, the sleeves being disposed in the orifices in the rail chair, bolts which pass through the said sleeves, rail chair and transverse channel member, and a

- wedge-shaped member which is adapted to be disposed between the rail and the horizontal portion of the rail chair.
20. In a railroad tie, a transverse channel member, a rail chair, which has a horizontal portion and two side vertical portions, the vertical portions having orifices therethrough, the rail chair being disposed on the transverse channel member with the centers 5 of its orifices substantially in alignment with the centers of orifices in the said transverse channel member, lugs on sleeves, the sleeves 10 being disposed in the orifices in the rail chair, and a wedge-shaped member which is adapted to be disposed between the rail and 15 the horizontal portion of the rail chair.
- In testimony whereof we have signed our names to this specification in the presence of two subscribing witnesses.
